 THERAPEUTIC COMPOSITION COMPRISING
TETRACYCLINE AND A DIOXOLANE

Richard H. Johnson, Kalamazoo, and Donald P. Wallach, Richland, Mich., assignors to The Upjohn Company, Kalamazoo, Mich., a corporation of Delaware
No Drawing. Filed Apr. 7, 1959, Ser. No. 804,577
10 Claims. (Cl. 167—82)

This invention relates to a therapeutic composition of tetracycline and more particularly to a parenterally acceptable dosage form of tetracycline with a dioxolane vehicle.

Prior to the present invention the tetracycline compositions for parenteral administration have utilized water as the vehicle. However, the administration of such aqueous preparations have had the disadvantages of slow absorption and slow systemic distribution from the site of injection and trauma and pain at the site of injection.

The therapeutic compositions of the present invention comprise tetracycline and a dioxolane. The compositions can be either solutions or suspensions depending upon the particular form of tetracycline used, the concentration of the particular tetracycline and the presence of solubilizers. Advantageously the compositions can include a parenterally acceptable acid, a local anesthetic, a compound capable of providing a magnesium ion, and, as an aid to preparing the composition, a surfactant. Other antibiotics can be included in the compositions, especially novobiocin for its synergistic effect with tetracycline.

The compositions of the present invention are useful for the administration of tetracycline and are superior to aqueous tetracycline compositions from the therapeutic standpoint in that they produce higher blood levels of tetracycline and are less painful to the patient.

The dioxolane compounds suitable for the compositions of the present invention can be represented by the following graphic formula:

wherein

R is a hydrogen, methyl or ethyl;

R¹ is a hydrogen, methyl, or ethyl; and

R² is a hydrogen, methyl, carbinol, or ethylol.

The preferred compound is 2,2-dimethyl-1,3-dioxolane-4-methanol, wherein R and R¹ are methyl and R² is carbinol. The other dioxolane compounds of this group, suitable as a vehicle for tetracycline, are 1,3-dioxolane, 4-methyl-1,3-dioxolane, 1,3-dioxolane-4-methanol, 1,3-dioxolane-4-ethanol, 2,2-dimethyl-1,3-dioxolane, 2,2,4-trimethyl-1,3-dioxolane, 2,2-dimethyl-1,3-dioxolane-4-ethanol, 2,2-diethyl-1,3-dioxolane, 2,2-diethyl-4-methyl-1,3-dioxolane, 2,2-diethyl-1,3-dioxolane-4-methanol, 2,2-diethyl-1,3-dioxolane, 2-methyl-1,3-dioxolane, 2,4-dimethyl-1,3-dioxolane, 2-methyl-1,3-dioxolane-4-methanol, 2-methyl-1,3-dioxolane-4-ethanol, 2-ethyl-1,3-dioxolane, 2-ethyl-4-methyl-1,3-dioxolane, 2-ethyl-1,3-dioxolane-4-methanol, 2-ethyl-1,3-dioxolane-4-ethanol, 2-ethyl-2-methyl-1,3-dioxolane, 2,4-dimethyl-2-ethyl-1,3-dioxolane, 2-ethyl-2-methyl-1,3-dioxolane-4-methanol, 2-ethyl-2-methyl-1,3-dioxolane-4-ethanol.

The term tetracycline as used in the specification and claims herein shall be taken to include the pharmaceutically and physiologically acceptable free base, organic and inorganic salts, as well as chelates, esters, complexes, and

2

6-demethyl tetracycline and pyrrolidino-methyl-tetracycline.

The solubility of the free base in 2,2-dimethyl-1,3-dioxolane-4-methanol is greater than 250 mg./cc. and the inorganic acid salts such as the hydrochloride or phosphate are more slowly soluble and in concentrations of more than about 50 mg./cc. form suspensions. Whether the composition forms a solution or suspension in the dioxolane, however, the composition is therapeutically superior to the equivalent aqueous composition.

Current medical practice utilizes aqueous compositions having a tetracycline concentration of about 50 mg./cc. and 125 mg./cc. This invention enables a higher concentration of tetracycline up to 250 mg./cc. and more.

15 A concentration greater than 250 mg./cc. of an insoluble tetracycline increases the viscosity of the compositions and although compositions having this increased viscosity are suitable for veterinary purposes where use of a large needle is permissible, it is preferred that compositions for human use have a concentration of 250 mg./cc. or less. Of course, a lesser concentration can be used to the minimum for therapeutic efficacy.

Although compositions can be prepared having a tetracycline concentration from 1 mg. or less/cc. to about 25 500 mg./cc., it is preferred to prepare compositions having a concentration which is relevant to the usual dosage requirements. To this end the compositions are preferably supplied in unit dosage form, i.e., in single dose amounts of 1 or 2 cc. having 250 mg. of tetracycline or multiple dose amounts of 10 cc. having 2.5 g. of tetracycline.

30 In addition to the tetracycline, another antibiotic can be included in the compositions. Advantageously the additional antibiotic can serve to either broaden the antibacterial spectrum of the composition or exert a synergistic effect with the tetracycline against particular bacteria. Novobiocin can be added to the compositions of the present invention to follow the preference of current medical practice for the concurrent administration of tetracycline and novobiocin. Pencillin V can also be included with tetracycline in the compositions and the two antibiotics can be present either as separate ingredients or in the form of the tetracycline salt of penicillin V.

35 A water soluble and parenterally acceptable acid is advantageously included in the compositions of the present invention wherein the tetracycline is present as the acid addition salt. The addition of an acid to the composition increases further the rapid absorption and systemic distribution of the antibiotic.

40 Citric acid is the preferred acid. A concentration of about 10% w/v. citric acid is preferred for those compositions having a tetracycline concentration of about 125 mg./cc. Ascorbic acid can also be used as well as other parenterally acceptable acids such as gluconic acid, lactic acid and glycine hydrochloride.

45 45 A local anesthetic agent is advantageously incorporated into the compositions of the present invention as a further aid in the reduction of pain of the injection. The anesthetic effect will begin several minutes after injection and lasts for several hours, onset and duration of action

60 ranging with the particular agent used. A concentration of about 0.5 to 2% w/v. is used depending upon the particular local anesthetic agent. Local anesthetics such as butethamine, dibucaine, procaine, tetracaine, and lidocaine, as well as others are suitable. The hydrochloride salts are usually used for those compositions having an acid present.

65 Pain can be further reduced by the inclusion of a compound capable of providing a magnesium ion, such as magnesium chloride and magnesium gluconate. Magnesium chloride is used in a preferred concentration of about 2 moles or more to 1 mole of tetracycline.

70 A surfactant in a concentration of about 0.5% is ad-

vantageously present as an adjuvant to the preparation and administration of those compositions forming suspensions. This agent aids in the suspending of the insoluble particles in the dioxolane, insuring accurate dosage when aliquots of the composition are administered. The surfactant also prevents "freezing" of the syringe and clogging of the lumen of the hypodermic needle. Polyoxyethylene sorbitan monolaurate is preferred.

The compositions of the present invention are best prepared in final form at the time of administration by simply adding the dioxolane from one container to the dry powder tetracycline mixture in the other container and shaking until dispersed.

In preparing the dry powder mixture the various dry ingredients are first reduced to a finely divided state. Examples of the many ways in which comminution can be carried out can be found in chapter 11 of Remington's Practice of Pharmacy, 11th edition, Mack Publishing Company, Easton, Pennsylvania, U.S.A., 1956. The preferred method of reducing the particle size of the various ingredients is by use of an air micronizer; particles so reduced by this method will hereinafter be described as micronized.

When the final composition is to be a suspension and a surfactant is employed, the latter is deposited over the surface of the tetracycline particles. If the surfactant is fluid, it can be sprayed over the powder; however, better distribution is obtained if the surfactant is dissolved in a volatile fluid (which is not a solvent for the tetracycline) and the solution sprayed onto the tetracycline. Alternatively, a slurry can be made of the tetracycline and the surfactant-solvent solution, and the solvent allowed to evaporate. The "coated" tetracycline particles are then blended with the remaining ingredients until uniformly dispersed.

After blending the powders, the mixture in measured amounts is filled into suitable containers, preferably glass vials, and sterilized by exposure to ethylene oxide or by other suitable means. The vial is then capped or otherwise sealed.

The dioxolane is sterilized by suitable methods, preferably by passing through a sterilizing filter, and aseptically filled into a container which is then sealed.

The compositions of the present invention are prepared at the time of administration by mixing the dioxolane with the tetracycline powder blend.

The following examples are illustrative of the process and products of the present invention, but are not to be construed as limiting.

Example 1

Tetracycline base, milled _____ G. 287.5
 α-Diethylamino-2,6-aceto-xylidide _____ 40

The powders are bolted through No. 9 bolting cloth and thoroughly blended. The blended powder mixture is filled into vials, each vial containing 327.5 mg. of powder mixture. The vials are sterilized by exposure to ethylene oxide vapors and capped.

Two cubic centimeter glass ampoules are aseptically filled with sterile 2,2-dimethyl-1,3-dioxolane-4-methanol and sealed.

At the time for administration the 2,2-dimethyl-1,3-dioxolane-4-methanol is added to the vial containing the antibiotic in an amount sufficient to make 2 cc. of solution. The vial is shaken until the powders are dissolved and the solution withdrawn in a syringe and administered, preferably intramuscularly. When so used, the preparation gives less pain and higher tetracycline blood levels than an equivalent composition utilizing an aqueous vehicle.

Example 2

Tetracycline base, milled _____ G. 575
 α-Diethylamino-2,6-aceto-xylidide _____ 40

5 The powders are bolted through No. 9 bolting cloth and thoroughly blended. The blended powder mixture is filled into vials, each vial containing 615 mg. of powder mixture. The vials are sterilized by exposure to ethylene oxide vapors and capped.

6 Two cubic centimeter glass ampoules are aseptically filled with sterile 2,2-dimethyl-1,3-dioxolane-4-methanol and sealed.

At the time for administration the 2,2-dimethyl-1,3-dioxolane-4-methanol is added to the vial containing the antibiotic in an amount sufficient to make 2 cc. of solution. The vial is shaken until the powders are dissolved and the solution withdrawn in a syringe and administered, preferably intramuscularly. When so used, the preparation gives less pain and higher tetracycline blood levels than an equivalent composition utilizing an aqueous vehicle.

Example 3

G. 20 Tetracycline base, milled _____ 287.5
 Calcium acid novobiocin, micronized _____ 143.7
 α-Diethylamino-2,6-aceto-xylidide _____ 40

The powders are bolted through No. 9 bolting cloth and thoroughly blended. The blended powder mixture is filled into vials, each vial containing 471.2 mg. of powder mixture. The vials are sterilized by exposure to ethylene oxide vapors and capped.

Two cubic centimeter glass ampoules are aseptically filled with sterile 2,2-dimethyl-1,3-dioxolane-4-methanol and sealed.

At the time for administration the 2,2-dimethyl-1,3-dioxolane-4-methanol is added to the vial containing the antibiotics in an amount sufficient to make 2 cc. The vial is shaken to uniformly distribute the antibiotics and the final compositions withdrawn in a syringe and administered, preferably intramuscularly. When so used, the preparation gives less pain and higher tetracycline blood levels than an equivalent composition utilizing an aqueous vehicle.

Example 4

G. 30 Tetracycline phosphate, micronized, 1% lecithin coated _____ 287.5
 Citric acid anhydrous, micronized _____ 222
 α-Diethylamino - 2,6-aceto - xylidide hydrochloride, micronized _____ 44

The dry powders are mixed together until uniformly dispersed. 553.5 mg. of the mixture are filled into a vial, sterilized with ethylene oxide and capped.

50 1.9 cc. of sterilized 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 5

G. 65 Tetracycline phosphate, micronized _____ 287.5
 Citric acid, anhydrous, micronized _____ 220
 α - Diethylamino - 2,6 - aceto - xylidide hydrochloride, micronized _____ 44
 Polyoxyethylene sorbitan monolaurate _____ 10

70 The polyoxyethylene sorbitan is dissolved in about 250 cc. of chloroform and the solution mixed with the tetracycline until the tetracycline particles are uniformly wetted. The chloroform is allowed to evaporate and the cake dried at 40° C. for 2 hours. The tetracycline cake is comminuted and the powder blended with the remain-

ing ingredients. 561.5 mg. of the mixture is filled into a vial, sterilized with ethylene oxide, and capped.

1.9 cc. of 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 6

	G.
Tetracycline phosphate, micronized-----	287.5
Citric acid, anhydrous, micronized-----	220
Tetracaine hydrochloride, micronized-----	44
Polyoxyethylene sorbitan monolaurate-----	10

The polyoxyethylene sorbitan is dissolved in about 250 cc. of chloroform and the solution mixed with the tetracycline until the tetracycline particles are uniformly wetted. The chloroform is allowed to evaporate and the cake dried at 40° C. for 2 hours. The tetracycline cake is comminuted and the powder blended with the remaining ingredients. 561.5 mg. of the mixture is filled into a vial, sterilized with ethylene oxide and capped.

1.9 cc. of sterilized 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 7

	G.
Pyrrolidino - methyl - tetracycline citrate, micronized-----	287.5
Citric acid, anhydrous, micronized-----	220
Tetracaine hydrochloride, micronized-----	44
Polyoxyethylene sorbitan monolaurate-----	10

The polyoxyethylene sorbitan is dissolved in about 250 cc. of chloroform and the solution mixed with the tetracycline until the tetracycline particles are uniformly wetted. The chloroform is allowed to evaporate and the cake dried at 40° C. for 2 hours. The tetracycline cake is comminuted and the powder blended with the remaining ingredients. 561.5 mg. of the mixture is filled into a vial, sterilized with ethylene oxide and capped.

1.9 cc. of sterilized 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 8

	G.
Tetracycline-Penicillin V salt, micronized-----	500
Citric acid, anhydrous, micronized-----	200
α - Diethylamino - 2,6 - aceto - xylidine hydrochloride, micronized-----	44
Polyoxyethylene sorbitan monolaurate-----	10

The polyoxyethylene sorbitan is dissolved in about 500 cc. of chloroform and the solution mixed with the tetracycline until the tetracycline particles are uniformly

wetted. The chloroform is allowed to evaporate and the cake dried at 40° C. for 2 hours. The tetracycline cake is comminuted and the powder blended with the remaining ingredients. 774 mg. of the mixture is filled into a vial, sterilized with ethylene oxide and capped.

1.9 cc. of 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 9

	G.
Tetracycline phosphate, micronized-----	575
Polyoxyethylene sorbitan monolaurate-----	10

The polyoxyethylene sorbitan monolaurate is dissolved in about 500 cc. of chloroform and the solution mixed with the tetracycline until the tetracycline particles are uniformly wetted. The chloroform is allowed to evaporate and the cake dried at 40° C. for 2 hours. The tetracycline cake is comminuted. 585 mg. of the powder is filled into a vial, sterilized with ethylene oxide and capped.

1.9 cc. of 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. of suspension. The vial is shaken to suspend the antibiotic and the suspension withdrawn in a syringe and administered, preferably intramuscularly. When so used, the preparation gives less pain and higher tetracycline blood levels than an equivalent composition utilizing an aqueous vehicle.

Example 10

	G.
6-demethyl tetracycline, milled-----	287.5
α-Diethylamino-2,6-aceto-xylidine-----	40

The powders are bolted through No. 9 bolting cloth and thoroughly blended. The blended powder mixture is filled into vials, each vial containing 325.5 mg. of powder mixture. The vials are sterilized by exposure to ethylene oxide vapors and capped.

1.9 cc. of sterilized 2,2-dimethyl-1,3-dioxolane-4-methanol is aseptically filled into a glass vial and sealed.

At the time for administration the 2,2-dimethyl-1,3-dioxolane-4-methanol is added to the vial containing the antibiotic in an amount sufficient to make 2 cc. The vial is shaken to disperse the antibiotic and the composition withdrawn in a syringe and administered, preferably intramuscularly. When so used, the preparation gives less pain and higher tetracycline blood levels than an equivalent composition utilizing an aqueous vehicle.

It is to be understood that the invention is not to be limited to the exact details of operation or exact compounds shown and described, as obvious modifications and equivalents will be apparent to one skilled in the art, and the invention is therefore to be limited only by the scope of the appended claims.

65 We claim:

1. A therapeutic composition for parenteral administration comprising tetracycline as an essential active ingredient and, as a vehicle therefor, 2,2-dimethyl-1,3-dioxolane-4-methanol.
2. The composition of claim 1 wherein the tetracycline is the tetracycline free base.
3. The composition of claim 1 wherein the tetracycline is a acid addition salt of tetracycline free base.
4. The composition of claim 1 wherein the tetracycline is the penicillin V salt of tetracycline free base.

5. The composition of claim 1 wherein the tetracycline is 6-demethyl tetracycline.

6. The composition of claim 1 wherein the tetracycline is pyrrolidino-methyl-tetracycline.

7. A therapeutic composition for parenteral administration comprising a pharmacologically acceptable acid addition salt of tetracycline free base as an essential active ingredient, a non-toxic, parenterally acceptable, water soluble acid, and, as a vehicle therefor, 2,2-dimethyl-1,3-dioxolane-4-methanol.

8. A therapeutic composition for parenteral administration comprising from about 5 mg./cc. to about 500 mg./cc. of tetracycline as an essential active ingredient, and, as a vehicle therefor, 2,2-dimethyl-1,3-dioxolane-4-methanol.

9. A therapeutic composition for parenteral administration comprising about 12.5% tetracycline phosphate, about 10% citric acid, about 2.0% α -diethylamino-2,6-aceto-xylidide hydrochloride, about 0.5% polyoxyethylene sorbitan monolaurate and 2,2-dimethyl-1,3-dioxolane-4-methanol.

10. A therapeutic composition for parenteral adminis-

tration comprising about 12.5% tetracycline phosphate, about 10% citric acid, about 2.0% tetracaine hydrochloride, about 0.5% polyoxyethylene sorbitan monolaurate and 2,2-dimethyl-1,3-dioxolane-4-methanol.
